(57) **CLAIM**

The ornamental design for a beverage bottle, as shown and described.

DESCRIPTION

FIG. 1 is a perspective view of a beverage bottle;

FIG. 2 is a front view of FIG. 1;

FIG. 3 is a rear view of FIG. 1;

FIG. 4 is a left-side view of FIG. 1;

FIG. 5 is a right-side view of FIG. 1;

FIG. 6 is a bottom view of FIG. 1; and,

FIG. 7 is a top view of FIG. 1.

Colors shown in the drawings form no part of the claimed design. Shadows and reflections do not represent any particular color, material, texture, or finish.

The broken lines in the drawings depict portions of the beverage bottle that form no part of the claimed design.

1 Claim, 7 Drawing Sheets
